ATTORNEY

UNITED STATES PATENT OFFICE.

FRANK A. BUA, OF LODI, NEW JERSEY.

TUNING DEVICE FOR VIOLINS.

Application filed March 19, 1924. Serial No. 700,339.

To all whom it may concern:

Be it known that I, FRANK A. BUA, a citizen of the United States, residing at Lodi, in the county of Bergen and State 5 of New Jersey, have invented new and useful Improvements in Tuning Devices for Violins, of which the following is a specification.

My invention relates to violins and analogous musical instruments, and it has for 10 its object to provide a simple, compact, easily adjusted and efficient device through the medium of which the several strings of a violin may be expeditiously and easily 15 tuned to correct pitch.

The tuning device of my invention is also advantageous because it is susceptible 20 of being embellished so that when applied to a violin it will enhance rather than detract from the finished appearance of the violin.

To the attainment of the foregoing, the invention consists in the improvement as 25 hereinafter described and definitely claimed.

25 In the accompanying drawings, forming part of this specification:

Figure 1 is a plan view showing the arrangement of my novel device between the tail piece and the bridge of a violin.

30 Figure 2 is a transverse section taken in the plane indicated by the line 2—2 of Figure 1, looking toward the right.

Figure 3 is an end elevation of my novel device in proper relation to violin strings.

35 Figure 4 is an enlarged detail section taken in the plane indicated by the line 4—4 of Figure 2.

Similar numerals of reference designate 40 corresponding parts in all of the views of the drawings.

In Figure 1, the tail piece of a violin is designated by 1, and the violin bridge is designated by 2, while the four strings are designated by 3.

45 My novel device for the tuning of the four strings to correct pitch is arranged between the tail piece 1 and the bridge 2 as is clearly shown in Figure 1, while the arrangement of the device relative to the 50 violin strings 3 is brought out in Figure 1 and also in Figures 3 and 4.

Among other elements my novel device comprises a concavo-convex body 4, prefer-

ably of sheet metal. The said body 4 is provided with four apertures 5 and is also 55 provided with curvilinear lips 6 and 7, the lip 6 being shown higher than the lip 7 in about the extent indicated, and the lip 6 being arranged adjacent to the bridge 2 while the lip 7 is arranged adjacent to 60 the tail piece 1.

In addition to the body 4 the device comprises a plurality of headed screws 8, and nuts 9 of sleeve type, the said nuts 9 having rounded lower ends 10 to engage the 65 strings without injury thereto. When desired the upper ends of the nuts 9 which are enlarged as illustrated may be knurled as indicated by 11 in Figure 3 so as to facilitate the turning of the nuts through 70 the medium of the thumb and forefinger of the performer. The screws 8 receive the strings 3 in the slots 12 of the screws, and hence there is no liability of the screws 75 being turned about their axes when the nuts 9 are turned down on the strings.

The novel tuning device being arranged on and engaged with the several strings 3 in the manner illustrated, all that is necessary to tune the strings to correct pitch is 80 to adjust the nuts 9 on the screws 8. Manifestly this may be quickly and easily done, and the correct pitch readily attained.

It will be apparent from the foregoing that not only the body 4, but the nuts 85 9 may be nickel plated or otherwise embellished with a view to enhancing the finished appearance of the violin.

I have entered into a detailed description of the construction and relative arrangement of the parts embraced in the present and preferred embodiment of my invention in order to impart a full, clear and exact understanding of the said embodiment. I do not desire, however, to be understood 90 as confining myself to the specific construction and relative arrangement of parts inasmuch as in the future practice of the invention various changes and modifications may be made such as fall within the scope 95 of my invention as defined in my appended claim.

Having described my invention, what I claim and desire to secure by Letters-Patent, is:—

A tuning device of the character described

comprising an apertured concavo convex body formed with a relatively short rear wall and a relatively long forward wall, curvilinear lips formed on the upper ends of the walls, split headed bolts arranged in parallelism and passing through the apertures of the body, and nuts of the sleeve comprising an apertured concavo convex type mounted on the screws and having their lower ends normally arranged at a point between the lips of the body. In testimony whereof I affix my signature.

10

FRANK A. BUA.
